UNITED STATES PATENT OFFICE.

SAMUEL LAPIN, OF PHILADELPHIA, PENNSYLVANIA.

CLEANING-PAD.

1,362,426.

Specification of Letters Patent. Patented Dec. 14, 1920.

Application filed October 16, 1919. Serial No. 331,007.

To all whom it may concern:

Be it known that I, SAMUEL LAPIN, a citizen of the United States of America, residing at Philadelphia, in the county of Philadelphia and State of Pennsylvania, have invented new and useful Improvements in Cleaning-Pads, of which the following is a specification.

The object of the invention is to provide a simple, relatively inexpensive, convenient and compact device adapted to be carried in the satchel or hand-bag for removing spots and stains from fabric as of clothing, and from shoes of leather, canvas, buckskin, 15 kid skin, suede, etc., as well as from gloves and similar articles of wearing apparel, the same being provided with means not only for removing stains but also for restoring polish, raising the nap of the cloth, restoring 20 the original appearance to fabric which has become glazed by wear or the accumulation of grease and the like, variations in the specific functions of the utensil being dependent mainly upon variations in the 25 character of the detergent or other filling with which the pad may be supplied according to its proposed specific use, and to these ends the invention consists in a construction and combination of parts of which 30 a preferred embodiment is shown in the accompanying drawing, it being understood that changes in form, proportion and details may be resorted to within the scope of the claims without departing from the 35 principles involved.

In the drawings:

Figures 1 and 2 are opposite side views and Fig. 3 a transverse sectional view of one form of pad embodying the invention.

Figs. 4 and 5 are respectively plan and side views of a modified construction of the same.

Figs. 6 and 7 are respectively side and plan views of another modification.

Essentially the device consists of a casting 10 of cylindrical or analogous form containing a filling 11 of detergent material such as a cake of soap, or soap powder or whiting covered by a rubbing surface 12 of fabric which may be more or less of an open mesh or weave such as cheesecloth, and should be convexed as shown clearly in Fig. 3 so as to project beyond the rim 13 for rubbing contact with an object without 50 bringing the rim into engagement there-

with. To hold the rubbing surface in its convexed form and supplement the action of the filling material in this connection a spacing block 14 of cork or other preferably yielding material may be arranged at 60 the center of the cylindrical casing. At the opposite side of the pad there is arranged a diaphragm 15 having an abrasive surface as of emery or carborundum held in place by a flange 16 or the equivalent thereof, and 65 in the construction illustrated in Figs. 1 to 3 inclusive a filler block 17 is arranged in rear of said abrasive diaphragm and is fitted at its periphery with brush bristles 18, said filling block being supported at its 70 inner side by an internal flange 19 which serves to space the same from the compartment in which the detergent filler is located.

In the construction illustrated in Figs. 4 and 5 the cylinder 20 is provided with a 75 filler 21 of detergent material and is closed at opposite sides by the flexible fabric rubbing surface 22 and the abrasive diaphragm 23 while in Figs. 6 and 7 the illustrated construction corresponds with that shown 80 in Figs. 4 and 5 with the addition of an abrasive panel 24 located on the exterior surface of the cylindrical wall.

In practice the detergent material contained by the pad is adapted to sift or 85 otherwise find its way through the interstices of the fabric rubbing surface to be applied to the garment from which a spot or stain is to be removed, the abrasive surface being employed where the spot offers 90 particular resistance or in order to raise the nap of the cloth after the cleaning thereof, it being obvious that water may be used as an agency in the cleaning operations particularly where the detergent ma- 95 terial consists of soap or soap powder.

For example in removing grease, food and road stains from heavy clothing, velvet, cloth spats, leather belts, satchels, etc., the proper procedure is to saturate the 100 cloth or fabric surface of the pad with water and rubbing the palm of the hand until a soap lather has been produced and then apply to the stain and rub until the spot has vanished; and for removing shine 105 from serge and similar material the rubbing conducted as before indicated should be continued until the lather has been absorbed by the material after which the latter should be wiped with a dry clean cloth 110

and the reverse or abrasive surface of the pad used gently against the nap of the cloth to raise the latter. Obviously the device may also be employed efficiently in removing ink, fruit and other stains from the hands and finger nails, the fabric rubbing surface of the pad serving to effect the cleaning while the reverse or abrasive side of the pad performs the function of the 10 emery board generally used for the finger nails.

Other and analogous uses will suggest themselves along the same general lines as a means of avoiding the necessity, particularly in traveling, of subjecting garments or portions thereof to cleaning operations which necessitate temporary discontinuance of the use thereof.

What is claimed is:

- 20 1. A pad for the purpose indicated comprising a casing, a detergent filler, an outwardly convexed rubbing surface holding the filler in place but being penetrable by the material of the filler, and a spacer carried by the casing and surrounded by the

filler and disposed to support the rubbing surface in its convexed shape.

2. A pad for the purpose indicated comprising a casing, a detergent filler, an outwardly convexed rubbing surface, holding 30 the filler in place and being penetrable by the material of the filler, and a yielding spacer carried by the casing and surrounded by the filler and bearing against the rubbing surface to maintain the same in outwardly convexed form.

3. A pad for the purpose indicated comprising a casing, a detergent filler, a fabric rubbing surface penetrable by the material of the filler and closing one side of the casing and maintaining the filler in place, and a centrally disposed cork spacer carried by the casing and surrounded by the filler and bearing against the fabric rubbing surface to maintain the same in outwardly convexed form.

In testimony whereof he affixes his signature.

SAMUEL LAPIN.
